AUTOMATIC DRAFT REGULATING
DEVICE FOR BOILERS

Wilhelm Blasberg, Chicago, Ill.

Application April 25, 1932. Serial No. 607,421

3 Claims. (Cl. 236—26)

The invention relates to apparatus for automatically regulating the opening and closing of the draft door and the chimney damper commonly provided on heating boilers.

5 The object of the invention is to automatically close the draft door and the chimney damper when a certain pressure has been obtained in the boiler and to open the two again when the pressure in the boiler falls below the desired 10 degree.

Another object of the invention is to make it possible to close or open the draft door and the chimney damper of the heating boiler automatically either entirely or partly according to the pressure desired in the boiler.

15 Other objects of the invention not specifically mentioned may be easily ascertained and understood from the following description in connection with the accompanying drawings forming a part thereof. It is however to be noted, that the invention is not to be limited and restricted to the exact formation and construction shown in the drawings and described in the specification, but that the invention is only to be limited by the 20 scope of the claims appended hereto.

In the drawings illustrating a preferred embodiment of the invention

Figure 1 is a front view of a heating boiler equipped with the automatic apparatus according to the present invention.

Figure 2 is a side view indicating the connection with the chimney damper.

Figure 3 is a detail view of the regulating levers used in connection with the present invention showing them in a position in which the draft door and the chimney damper would be opened.

Figure 4 is a view similar to Figure 3 also showing a position in which the draft door 40 and the chimney damper would be opened, but in this case chain 28 is a few links shorter fastened.

Figure 5 is a view taken on line 5—5 in Figure 3.

45 A boiler 6 is equipped with the usual draft door 7 and the usual chimney damper 8. The common practice is to regulate these two members independently of each other; namely, to regulate the draft door by means by a regulator and the chimney damper by hand. This is sometimes inconvenient, especially when the fireman taking care of the boiler is not exclusively occupied therewith, but has some other duties to attend to, so that he can not always 50 be right by the boiler to watch it. To regulate the opening and closing of the two said members a hanger 9 may be fastened to the ceiling of the boiler room in any desired and convenient manner. A pressure regulator 10 of a well known 55 construction having a plunger 11 connected with

a membrane in the regulator is connected with the interior of the boiler by means of a pipe 12. A bracket 13 is rigidly fastened to the regulator or may be an integral part thereof and extends upwardly of the regulator. An actuating lever 14 is pivotally mounted on the bracket 13 and the free end of the plunger 11 is pivotally fastened to the actuating lever 14. A counter weight 15 is adjustably mounted on the actuating lever and is arranged on the same lever arm 65 with the plunger connection in relation to the fulcrum bracket 13. Adjacent the end of the other lever arm i. e. the end of that part of the lever 14 on the other side of the fulcrum bracket a sheave 16 is rotatably mounted.

Along one edge of the hanger 9 a bar of flat iron is located as shown at 17 and is fastened to the hanger in any suitable and desired manner. It is spaced from the hanger by means of spacer blocks 18. In this bar and in 70 the hanger 9 a plurality of corresponding holes 19 are provided. A second bar 20 of flat iron is fastened to the other side of the hanger and extends along the other longitudinal edge thereof as clearly shown in the drawings. This second 75 bar is also kept at a distance from the hanger by means of spacer blocks 21. The lever 14 is located so that it extends between the second bar 20 and the hanger 9 and that the part of said lever located between these two parts may 80 swing upwardly and downwardly and will be guided in this movement by the two mentioned 85 members.

A regulating lever 22 is pivotally mounted between the hanger 9 and the flat iron bar 17. The 90 fulcrum for this lever is indicated at 23. On one end of the regulating lever a counter weight 24 is arranged and the part adjacent this weight is located between the flat bar 17 and hanger 9. A pin 25 is adapted to be inserted in a pair of 100 corresponding holes 19 in the hanger and the flat bar 17, so that the swinging movement of the regulating lever may be limited by said pin. Adjacent the free end of the regulating lever a plurality of holes 26 is provided for a purpose 105 to be described later on. On the draft door 7 a chain 28 is fastened in any suitable and convenient manner. The free end of this chain is then connected to the regulating lever 22 by 110 means of a hook or the like extending therethrough into one of the holes 26, so that the working length of the lever arm at the right hand side of the fulcrum in the drawings may be shortened and lengthened at will.

115 In the chimney pipe 29 the damper is rotatably mounted by means of a shaft 30 or the like and on one end of said shaft which extends outwardly of the pipe an adjusting lever 31 is rigidly mounted. On the free end of the adjusting lever 120

a weight 32 is arranged and between the said weight and the shaft a chain 33 is fastened to the lever. On the ceiling of the boiler room a chain pulley 34 is arranged and the chain 33 is trained over this pulley.

A manipulating lever 35 is pivotally fastened to the hanger 9 as indicated at 36, and one of its ends extends between the flat bar 17 and the hanger and is provided with a plurality of holes 37, to one of which the free end of the damper chain 33 may be selectively fastened. The movement of the lever portion extending between the flat iron bar 17 and the hanger 9 may be selectively limited by means of a pin 38, which can be inserted in any pair of corresponding holes in the hanger and the flat iron bar.

The sheave 16 on the actuating lever 14 is located so that it is arranged above the right hand end in the drawings of the adjusting lever 22 and below the same end of the manipulating lever 35.

The apparatus according to the present invention works as follows:

The pressure in the boiler 6 will actuate the membrane in the regulator 10 which in turn will move the plunger 11 upwardly with increasing pressure or downwardly with decreasing pressure in the boiler. Upon upward movement of the plunger 11 sheave on the end of the adjusting lever 14 will engage the lever 22 and pivot the same so that the counter weight 24 will be lifted and the end of the lever on which the chain 28 is fastened will move downwardly. This movement will permit the draft door 7 to move into closing position by its own weight. As the pressure decreases the sheave end of the lever 14 will move upwardly and the counter weight 24 will move downwardly lifting the chain 28 upwardly whereby the draft door 27 will be opened. At the same time that the sheave 16 forces the regulating lever 22 downwards, it will be disengaged from the manipulating lever 35 and herewith permit the weight 32 to swing downwardly thereby pivoting the chimney damper into closing position.

If, therefore, the pin 38 in Figure 3 is located in the uppermost hole 19 and the pin 25 is removed then the damper and the draft door will be closed simultaneously.

If the pin 38 in Figure 3 is inserted in the lowermost hole 19 and the pin 25 is removed then the damper 8 will stay open while the draft door 27 will close under its own weight.

If in Figure 4 the pin 38 is inserted in the uppermost hole 19 and the pin 25 is arranged as shown then the damper will be closed first and after that the draft door will also move into closed position. In this case the chain 28 should be shortened by a few links.

The last described case is the most important because it is possible in this manner to keep all the heat in the boiler and prevent it from escaping from the flue. The use of the first two cases depends on the weather and the kind of fuel used.

The above description shows clearly that the draft door and the chimney damper of a boiler equipped with the apparatus according to the present invention can be automatically closed and opened respectively in accordance with the pressure in the boiler, and that the degree of closing and opening of said members may be adjusted and regulated by means of the stop pins 25 and 38 and in addition to that by means

of the varying length of the lever arms to which the chains 28 and 33 respectively are fastened.

Having described my invention and how the same operates I claim as new and desire to secure by Letters Patent:

1. In combination with a boiler having a regulator connected with the interior thereof, a draft door and a chimney damper, automatic draft regulating means comprising a plunger actuated by said regulator, an actuating lever pivotally mounted on said regulator having a counterweight at one end and a sheave at the other end, said lever adapted to be pivoted by said plunger, a hanger, means carried by said hanger for guiding movement of the sheave end of the said actuating lever, a regulating lever pivotally mounted below said actuating lever on said hanger and having flexible connection with said draft door, a manipulating lever pivotally mounted on said hanger above said actuating lever and having flexible connection with said chimney damper, said sheave being adapted to engage one end of said regulating and manipulating levers whereby movement of said sheave will serve to open or close said damper and said draft door.

2. In combination with a boiler having a regulator connected with the interior thereof, a draft door and a chimney damper, automatic draft regulating means comprising a plunger actuated by said regulator, an actuating lever pivotally mounted on said regulator having a counterweight at one end and a sheave at the other end, said lever adapted to be pivoted by said plunger, a hanger, a guide bar mounted on said hanger, the sheave end of said actuating lever being slidably mounted between said bar and said hanger, a regulating lever pivotally mounted below said actuating lever on said hanger and having flexible connection with said draft door, a manipulating lever pivotally mounted on said hanger above said actuating lever and having flexible connection with said chimney damper, said sheave being adapted to engage one end of said regulating and manipulating levers whereby movement of said sheave will serve to open or close said damper and said draft door.

3. In combination with a boiler having a regulator connected with the interior thereof, a draft door and a chimney damper, automatic draft regulating means comprising a plunger actuated by said regulator, an actuating lever pivotally mounted on said regulator having a counterweight on one end and a sheave at the other end, said lever adapted to be pivoted by said plunger, a hanger, a guide bar mounted upon one face of said hanger and adapted to guide movement of the sheave end of said actuating lever, a regulating lever pivotally mounted below said actuating lever on said hanger and having flexible connection with said draft door, a manipulating lever pivotally mounted on said hanger above said actuating lever and having flexible connection with said chimney damper, a second guide bar mounted upon the other face of said hanger and adapted to guide movement of said regulating and manipulating levers, said sheave being adapted to engage one end of said regulating and manipulating levers whereby movement of said sheave will serve to open or close said draft door and damper.

WILHELM BLASBERG.
